UNITED STATES PATENT OFFICE.

FRANK C. BLISS, OF WASHINGTON, DISTRICT OF COLUMBIA, ASSIGNOR TO
ANSON S. TAYLOR AND WILLIAM B. ROBISON, TRUSTEES, OF SAME
PLACE.

DESIGN FOR A FLAG.

SPECIFICATION forming part of Design No. 24,992, dated December 17, 1895.

Application filed October 28, 1895. Serial No. 567,200. Term of patent 3 $\frac{1}{2}$ years.

To all whom it may concern:

Be it known that I, FRANK C. BLISS, a citizen of the United States, residing at Washington, in the District of Columbia, have invented a certain new and useful Design for Flags; and I do declare the following to be a full, clear, and exact description of the invention, such as will enable others skilled in the art to which it appertains to make and use the same, reference being had to the accompanying drawing, and to the letters of reference marked thereon, which forms a part of this specification.

The leading feature of my design consists of two broad stripes or longitudinal divisions, upon which appears a star of contrasting color and having the fanciful figure at its center, as shown.

The flag A is divided into two fields or longitudinal divisions or stripes B C, which are of contrasting colors, such as red and blue.

Upon these fields, at the center and extending into both of them, appears a star D of a third contrasting color, the said star having a fanciful figure E at its center. This figure E consists of an open ring F, within which is a vertical bar G having arms H extending from its ends toward the mouth of the open ring and a third and shorter arm I projecting horizontally from its center.

Having thus fully described my invention, what I claim, and desire to secure by Letters Patent, is—

The design for a flag herein shown and described.

In testimony whereof I affix my signature in presence of two witnesses.

FRANK C. BLISS.
